J. W. WOOD

DIRECTION INDICATOR FOR MOTOR CARS AND OTHER VEHICLES

Filed Oct. 11, 1926

ATTORNEYS

UNITED STATES PATENT OFFICE.

JOHN WILLIAM WOOD, OF CHRISTCHURCH, NEW ZEALAND.

DIRECTION INDICATOR FOR MOTOR CARS AND OTHER VEHICLES.

Application filed October 11, 1926, Serial No. 140,921, and in New Zealand July 30, 1926.

This invention relates to a direction indicator for motor-cars, that is to say an appliance for use by the driver in signalling his intention to turn the vehicle and refers 5 to that type of appliance wherein a direction-pointing device, such for instance as a representation of a human hand, is mounted upon a vertical axis to be turnable by the driver to cause such direction-pointing device to project either forwardly or laterally according to the direction it is the intention of the driver to proceed.

It is the object of the present invention to provide an appliance of this type of novel 15 and special construction whereby the said turning of the direction-pointing device may be conveniently performed by the driver from his position within the vehicle in such a manner as to permit of such direction-pointing device being turned through an angle of 180° thereby enabling an intention to turn to either right or left to be correctly indicated, while a further object is to provide a construction wherein the said turning 20 of the device from its forward to its lateral positions in either direction will automatically give an audible signal, as by momentarily sounding an electric horn, while a still further object of the invention is to provide 25 a construction of this nature wherein the turning of the direction-pointing device into its lateral positions to right or left will automatically complete an electric circuit by means of which the said device is illuminated.

Thus, by one movement of the controlling 30 device, the desired direction is indicated, the horn sounded, and the direction-pointing device illuminated.

With these and other objects in view the invention consists of the novel construction and arrangement hereinafter described.

In order that the nature of the invention and its construction may be clearly understood, it will now be fully described and explained with reference to the accompanying drawings, in which:—

Fig. 1—is a perspective view showing the indicator installed upon a motor-car,

Fig. 2—is a side elevation of the indicator,

Fig. 3—is a plan-view of the same in which a portion of the reflector and a portion of one of the wire-receiving lugs are

shown broken away to reveal the internal 55 arrangements,

Fig. 4—is a perspective view of the drum by means of which the turning of the direction-pointing device is attained,

Fig. 5—shows in perspective the said 60 drum and its mounting, illustrating the construction employed in automatically giving the audible signal and in controlling the illumination of the direction-pointing device,

Fig. 6—is a longitudinal section through 65 the arm carrying the direction-pointing device and illustrating a special construction employed in cases where it is desired that such direction-pointing device shall be employed also for indicating an intention to 70 stop the vehicle, and,

Fig. 7—is a plan-view of the construction shown in Fig. 6.

The construction comprises a cylindrical casing 1 disposed with its axis vertical and 75 adapted for attachment to the exterior of the car at an appropriate point, as for instance by means of a bracket 2 extending laterally from one side of the wind-shield 3 of the car.

Rotatably mounted within the said casing 1 is a drum 4 formed with a pair of peripheral grooves 5 and 6 in which are received a pair of wires or tensional connections 7 and 8 (Fig. 4) wound around the said drum in 80 opposite directions and each having one end attached thereto, while the remaining portions of such tensional connections extend to a desired position within the car at which 85 position the remaining ends of such connection are connected to a suitable device operable by the driver for the purpose of differentially tensioning such connection and thereby effecting the turning of the drum 4 in either direction within its said casing 1.

The said controlling device will preferably consist of a stationary mounting as 9 (Fig. 1) secured to a suitable fixed position within the car, such for instance as the dashboard 10.

Within the said stationary 100 mounting will be contained a rotatable drum to which the ends of the said connections are attached such drum being formed with a pair of peripheral grooves in which the said connections are wound in opposite directions in precisely the same manner as that of the drum 4 already described.

The rotatable mounting of the said drum

4 within the cylinder 1 is preferably accomplished by providing the said drum with a spindle as 12 which is rotatably received within a bearing consisting of a bore 13 (Fig. 5) formed in a downward extension 14 of the lower end of the cylinder 1 as shown in Fig. 2.

In construction the said cylindrical casing 1 is preferably divided along a circumferential line at a point corresponding with the portion of the drum 4 between the two wire-receiving grooves 5 and 6 of the latter for convenience in assembling the parts and placing the said wires 7 and 8 in position.

15 The said wires 7 and 8 are preferably of the Bowden-cable type, as here shown and consisting of a flexible wire extending through a housing the two ends of the latter being fixed one to the cylinder 1 and the other to the stationary mounting 9 of the aforementioned control. For this purpose the two parts of the cylinder are formed with a pair of outwardly projecting lugs 15 and 16, one upon each part, and which lugs 20 are adapted to fit together face-to-face when such parts are assembled, as clearly shown in Fig. 2. In corresponding parts of the contacting faces of the lugs 15 and 16 are formed grooves 17 adapted when such parts 25 are assembled to constitute entrance passages for the wires to the interior of the cylinder and to receive and clamp the ends of the said housings of such wires, suitable means such as a screw 18 being employed to secure the lugs 15 and 16 firmly together.

In the case of the stationary mounting 9 of the control also a similar pair of grooved lugs will preferably be provided to clamp the other or opposite ends of the housings 40 and to provide the required entrance passages for the wires to the interior.

At its upper end the drum 4 is formed or provided with a suitable cover 19 to enclose the upper end of the cylinder 1, such cover being preferably formed with a downturned flange 20 to surround the wall of the cylinder 1 at its upper portion.

50 The direction-pointing device 21, consisting preferably of a representation of a human hand as here shown, is carried upon the outer end of a horizontal arm 22, the other or inner end of which is connected with the drum 4 so as to turn therewith.

In the preferred form of the construction, 55 as here shown the said inner end of the arm 22 is arranged to overlie the cover 19, which cover turns as one piece with the drum 4 and is preferably provided at its upper side with a boss 23 of square or other formation 60 to be non-rotatably received in a correspondingly shaped hole formed through the arm 22 near its said inner end. For the purpose of clamping the arm firmly in place upon the cover a screw-threaded stud 24, which conveniently consists of the upper end of the

drum-spindle 12, is arranged to project upwardly from the said boss to receive a clamping-nut 25 adapted to bear upon the upper side of the said arm.

Means are provided for illuminating the 70 direction-pointing device in order to render the same clearly visible at night. The said illuminating means consists of a reflector 26 encircling the arm 22 and arranged to face outward towards the said direction-pointing 75 device 21 and within which reflector are mounted a pair of electric lamps as 27 arranged one to either side of the arm 22.

In construction the said reflector 26 may conveniently be formed integral with the 80 portion of the arm 22 extending inward therefrom to its said point of connection with the drum, while the remaining or outer portion of such arm and the direction-pointing device 21 may be made separate and 85 detachably connected to such inner portion. This is preferably accomplished by forming horizontally through the centre of the reflector a suitable slot into which the end of the outer portion of the arm is adapted to be 90 slipped and secured therein by suitable means such for instance as a pin 27 passing transversely through the said slot and through the contained portion of the arm.

According to the present invention also 95 the lower end of the drum 4 and the adjacent inner face of the lower end of the cylindrical casing 1 are provided with electrical contacts 100 designed to control an electric circuit containing a horn or other audible signalling device in such a manner that the said circuit will thereby be closed when the drum is in process of turning to carry its direction-pointing device from one indicating position to another, such circuit being opened by the 105 contacts when the drum arrives at any of its said indicating positions.

In the preferred form of the construction as here shown (Fig. 5) this is accomplished by providing a brush or spring-plunger 28 110 mounted in the lower end of the cylinder and insulated therefrom, such brush being adapted to bear against the lower end of the drum 4 and thereby complete the circuit. The said lower end of the drum 4 is provided also, at those points at which the said brush or plunger 28 is adapted to bear when the direction-pointing device occupies any of its direction-indicating positions, with insulating surfaces consisting conveniently of pieces of electrically insulating material 29 115 inlaid in its surface in order that the said circuit may be broken when the device is in any of its said indicating positions. If desired however the said arrangement may be 120 reversed by mounting the brush or plunger 28 in the lower end of the drum and the insulating inlay 29 in the lower end of the cylinder.

According to the present invention also 125

the said lower end of the drum and casing will be provided with further electrical contacts controlling the supply of current to the aforementioned lamps 27, such contacts being so arranged to complete the circuit and so cause the lamps to light when the direction-pointing device occupies either of its lateral indicating positions.

In the preferred form of the construction as here shown the said contacts consist of a brush or spring-plunger 30 mounted in the said lower end of the drum 4 and a pair of contact surfaces 31 and 32 mounted in the lower end of the cylinder and each positioned at one of those points at which the brush 30 is adapted to bear when the direction-pointing device occupies its lateral positions so as to indicate turning to left or right, the arrangement being such that the said circuit will be completed only when the brush 30 is in contact with the surface 31 or the surface 32.

Each of the said contact surfaces 31 and 32 will be arranged to lie flush with the inner surface of the lower end of the cylinder and insulated therefrom. In cases where it is desired to cause the lamps to light when the direction-pointing device occupies its forward position, a third contact surface 33 similar in all respects will be provided at the point in the lower end of the cylinder at which the brush 30 bears when the direction-pointing device occupies its said forward position.

As in the case of the contacts controlling the audible signalling circuit already explained the positions of the said lighting circuit contacts may if desired be reversed by arranging the plunger 30 in the lower end of the cylinder and the contact-surfaces 31 and 32 in the lower end of the drum.

In the case of the audible signalling circuit one wire 33 will be connected by means of a terminal 34 with the brush 28 while the necessary return will be provided through the metal of the drum and cylinder which will be "earthing" to the chassis of the car.

In the case of the lighting circuit wires 35 from the electric system of the car will be connected by terminals 36 with the contact surfaces 31 and 32, while further wires 37 will connect one terminal of each lamp 27 with a terminal 38 connecting with the brush 30, the earth return through the metal of the device providing the remainder of the circuit.

In cases where it is desired to enable the device to be employed by the driver in indicating his intention to stop the vehicle, the hand, or other direction-pointing device 21 will be arranged to enable it to be turned upon the arm 22 from its normal horizontal position into a vertical position as indicated

in dotted lines Fig. 6, to give the desired signal.

For this purpose the outer end of the arm (Figs. 6 and 7) will terminate in a pair of vertically disposed cheeks 39 between which the direction-pointing device 21 is received and pivoted by means of a pin or the like 40 extending transversely through such cheeks and the intervening portion of the direction-pointing device to allow of the latter being turned upon such pivot in a vertical plane.

Formed integral with, or rigidly attached to the said portion of the direction-pointing device contained between the cheeks, is a pulley 41 having a peripheral groove in which is received a wire 42, preferably of the Bowden-cable type, having one end attached to the said pulley 41 while the remainder of such wire extends to a suitable hand-lever or other manipulable controlling device arranged within the car to be within convenient reach of the driver, such wire being led from the said pulley preferably through a suitable passage as 43 formed lengthwise through the arm 22 as here shown in Fig. 6.

The arrangement is such that the said hand or other direction-pointing device 21 will normally extend horizontally in line with the arm 22 for the purpose of giving the direction indications. When a stop signal is to be given however the said manipulable device controlling the wire 42 will be operated so as to tension such wire and so turn the direction-pointing device 21 upon its pivot 40 to project upward from the arm 100 as indicated in dotted lines Fig. 6.

When it is desired to restore the said direction-pointing device to its former or normal position after the stop signal has been given the said manipulable controlling device will be turned in the other or reverse direction thereby relaxing the tension of the wire 42 and so permitting the direction-pointing device to return either by gravity or with the assistance of a suitable spring.

In order to facilitate the said return movement of the direction-pointing device by gravity the said pivot 40 will preferably be arranged slightly upward and inward from the centre of such device, as here shown, in order that such device when in its upward position may have a tendency to turn by gravity into its normal or horizontal position.

In order to make a neat and compact arrangement there is preferably provided a flexible tube 44 extending from the indicator to the interior of the car and through which the said control wires and those of the electric circuits are led as here shown.

In operation, when it is the intention of the driver to proceed in a straight line ahead the drum 4 will be so placed as to cause the

direction-pointing device to extend forward-
ly as shown in full lines Fig. 1, while an in-
tention to turn to right or left will be indi-
cated by the driver in turning such drum so
as to cause the direction-pointing device to
project laterally in the desired direction as
indicated in dotted lines and during which
movement the audible signal will be given
by the said contacts while on arrival of the
direction-pointing device at its indicating
position the said lamps will be caused to
light by the operation of the said second set
of contacts thereby illuminating such direc-
tion-pointing device.

15 I claim:

1. A direction indicator for a vehicle com-
prising a vertically disposed cylindrical cas-
ing mountable upon the exterior of the ve-
hicle, a drum rotatable within said casing, a
20 cap enclosing the upper end of said casing
and fixed to said drum to rotate therewith, a
horizontal arm carrying a direction-point-
ing device fixed upon said cap to turn there-
with, and a pair of tensional connections
25 wound in opposite directions in peripheral
grooves around said drum and differentially
tensionable by a controlling device oper-
able by the driver for the purpose of turn-
ing said drum to cause said direction-point-
30 ing device to project forwardly or laterally
in either direction.

2. A direction indicator for a vehicle as
defined in claim 1 characterized in that each
35 of said tensional connections is of the Bow-
den-cable type and in that said casing is bi-
sected at a circumferential line correspond-
ing with a point between the said grooves of
the drum and in that the two said portions
40 of the casing are formed with corresponding
external lugs adapted to fit together face-to-
face and formed in their contacting surfaces
with grooves to receive the ends of the hous-
ings of said connections and to provide en-

trance passages for the latter to the interior
of the casing.

3. A direction indicator for a vehicle com-
prising a vertically disposed cylindrical cas-
ing, a rotatable cap closing the upper end of
the casing, a drum mounted in the casing
and fixed to the cap to rotate therewith, a
50 non-circular boss rigid with the upper sur-
face of the cap, an arm provided with an
opening of a shape corresponding to that of
the boss and receiving the latter there-
through, means for retaining the arm en-
gaged with said boss, a direction pointing
device carried by said arm and cable means
passing through the casing and connected
to the drum to provide for rotation of the
drum and arm in either direction.

4. A direction indicator comprising a
cylindrical casing having a bottom closure, a
rotatable cap closing the upper end of the
casing, a drum mounted in the casing and
provided with a spindle having its lower
65 end projecting downwardly through the bot-
tom closure of the casing and its upper end
formed to provide a threaded stud project-
ing upwardly through said cap, a square
70 boss rigid with the cap and receiving the
threaded stud therethrough, an arm pro-
vided at its inner end with a square opening
receiving said boss, a clamping nut carried
by the threaded stud and serving to hold
75 the arm in place, a direction pointing device
carried by said arm and cables passing
through openings formed in said casing and
secured to said drum to provide a means for
rotating the drum and arm in the desired
80 direction.

In testimony whereof I have hereunto
signed my name at the city of Christchurch,
in the Dominion of New Zealand the 13th,
day of September, 1926.

JOHN WILLIAM WOOD.
